UNITED STATES PATENT OFFICE.

JOHN FRED SCHNEIDER, OF NEW YORK, N. Y.

BOTTLE-LABELING MACHINE.

SPECIFICATION forming part of Letters Patent No. 771,940, dated October 11, 1904.

Application filed January 16, 1903. Serial No. 139,323. (No model.)

To all whom it may concern:

Be it known that I, JOHN FRED SCHNEIDER, a citizen of the United States, and a resident of the borough of Manhattan, in the city, county, and State of New York, have invented 5 certain new and useful Improvements in Bottle-Labeling Machines, of which the following is a full, clear, and exact specification.

My invention relates to bottling machinery; 10 and it consists of the hereinafter-described construction of parts and of the hereinafter-stated combinations of some parts into an automatic labeling - machine, resulting in the production of a simple efficient machine which 15 can be operated by hand or foot power or power from a transmission.

In the accompanying drawings, Figure 1 is 20 a front elevation of a machine embodying my invention, its parts being shown in position immediately after the labeling operation is completed and at the beginning of the operation 25 of gumming the pickers. Fig. 2 is a side elevation, and Fig. 3 a sectional view, some parts being shown in elevation, on line 3 3 indicated in Fig. 1, showing the parts of the machine in the same position as Fig. 1. Fig. 4 is a front elevation, like Fig. 1, of the upper part of the machine, showing the parts in position at the beginning 30 of the labeling operation immediately after the bottle to be labeled is inserted, the label being gummed and picked up. Fig. 5 is a similar view, like Fig. 4, showing, however, the parts in the act of affixing the label to the 35 bottle.

The frame of the machine consists of a stationary part or main frame and of a movable part or movable frame.

The stationary part or main frame is composed of uprights A, bound together by ties a and by tie-plates b and c, and of guide-rods d, secured to uprights A by brackets, (designated by the numeral 1.) The movable frame is composed of sleeves k, slid on rods d, and of tie-plates h and i. Tie-plate i is slotted, as shown in Fig. 1, and in the slot i' engages roller 120, loosely revolving on crank-pin 121 and held thereon by screw 105. Crank-pin 121 is secured in crank-disk K, set on the 45 forward end of the main driving-shaft B, and

thus the movable frame and the various mechanisms mounted thereon are reciprocated upon the stationary frame by the rotations of the main driving-shaft B, to which crank-disk K is rigidly secured.

The labels to be affixed to the bottles are piled face downward on table 8 and held there in position by flanges 11, 12, 13, and 14. Flange 12 is hinged to the front side of platform b by rod 15, mounted in lugs 16, and is 60 stationary, whereas the other flanges (11, 13, and 14) are adjustable to permit labels of different sizes and shapes to be used in the machine. Flange 12 is pressed by spring 17, held in position by screw 18 (which also secures the flange 12 to rod 15) against the squared ends of lugs 16. Flanges 11 and 12 are provided with inwardly-bent prongs, as shown at 19 in Fig. 3, overlapping the edges of the labels.

During the operation of the machine table 8 is gradually lifted by the mechanism, constructed as follows: Table 8 is provided with a stem 9 and by means of this stem entering the recess of screw-threaded shaft 3 is set 75 upon this shaft. This shaft is snugly fitted in boss 4, which is a part of platform b, and in the bore of bracket 5, secured to the same platform. Ratchet-wheel 6, provided with a corresponding screw-thread in its central bore, 80 is set on this shaft 3, resting on spring 7, which holds it snugly against boss 4. Rod 20, longitudinally movable in lug 22 and pivoted to rocking arm 21, carries on its forward end a pawl engaging with the ratchet-wheel 6. This 85

pawl turns the ratchet-wheel 6 the length of one tooth at every reciprocation of the arm 21. By this mechanism table 8 is pressed upward a proportionate distance as the quantity of the labels piled thereon is decreased by 90 the operations of the machine. Thus the pile of labels is always kept in a state of compression between table 8 and the prongs of flanges 11 and 12, which are stationary, being affixed in adjusted position to platform b by set-screws 95 passing through the slotted tails of these flanges into bores provided in platform b, which is permanently secured to uprights A of the stationary frame. The pressing downward of the opposite edges of the labels causes 100

the central portion of the labels to slightly bulge, whereby the gumming and picking-up operation of the labels is facilitated.

Above the platform *b* is located the frame 5 for holding the bottle during the process of applying the label thereto. This frame consists of rods 27, set in lugs 29, affixed to uprights *A* of the stationary frame, posts 25, set in heads 26 of rods 27, and of rod 24, set in 10 the heads of posts 25. Rods 27 are longitudinally movable in bearings 29. They are adjusted in desired position by screw-threaded wheels 30 and secured in adjusted position by lock-nuts 31. Posts 25 are also longitudinally 15 movable in heads 26 and are secured in desired position by set-screws 28. These adjustments are provided to enable bottles of different dimensions to be operated upon in the machine. On rod 24 a bolster 23, preferably 20 made of soft rubber, is affixed. This bolster 23 is concaved to better accommodate a bottle and hold it firmly in position against lateral displacement. The bottom of the bottle is supported in plate 41, having a circular flange 25 42. This plate is adjustably secured to bracket 37 by screw 40, passed through slot 39 of the bracket into a screw-threaded bore of plate 41. Bracket 37 is held to tie-plate *c* by angle-irons 38. This bracket is longitudinally movable 30 relatively to the plate *c*, the angle-irons 38 serving as guides for it. The part of bracket 37 adjoining plate *c* is bifurcated, and bell-crank lever 48 is fulcrumed between the prongs of the bifurcated part on pin 46, mounted in 35 bearings 47. The vertically-dependant arm of this bell-crank lever 48 is hinged to sleeve 44, wherein pin 43, secured in bracket 37, engages and is rigidly connected therewith when adjusted by screw 45. The horizontally-disposed 40 arm of lever 48 is hinged by pin 50 to rod 51, connecting it with the clutch mechanism, to be described later on.

The bottle resting in the frame in the position shown in Fig. 3 is held against the bolster 23, and the flanged plate 41 by pad 2, adjustably secured by means of its stem 59 in the head of lever 60. This lever is fulcrumed on pin 61, pillow'd in downwardly-projecting plugs of tie-plate *c*, as shown in Fig. 1, 45 and is actuated by mechanism mounted on the main driving-shaft *B*, to which it is connected by rod 63, hinged to the rear end of this lever. This rod is composed of two parts joined by extensible swivel-coupling *f* to permit adjustment of the motion of the lever. The motions of this mechanism are arranged to press the pad 2 upon the bottle during the period of affixing the label thereto and to withdraw it again when the operations are 50 completed to permit the removing of the labelled bottle from the machine.

The paste required to secure the labels to the bottle is applied to each label by bars 86 (see Fig. 1 and Fig. 3) when those bars are 55 brought in their lowest position then resting

upon the label. These bars 86 and levers 106, to which these bars are secured, (or made integral therewith,) serve also as pickers for lifting up the labels from the pile. Levers 106 are fulcrumed on pins 107, set in plate *h* of 70 the movable frame. Spring 108, held in the slotted head of screw-bolt 109, which is secured in the apex of plate *h*, acts by its ends against the short arms of levers 106, pressing them against stop-pins 110, and thus holds 75 levers 106 in such position that bars 86 rest upon the topmost label of the pile some distance inwardly from the edges thereof when the movable frame is brought into its lowermost position. 80

Bars 86 receive a fresh supply of paste every time the movable frame reaches its uppermost position, as shown in Fig. 1 of the drawings. The supply of paste is kept in trough 83, set on plate *c*. In this trough 85 shaft 87 is set in suitable bearings 88 and is driven by rope 89, passing over the grooved pulley 90, set on the end of shaft 87, and pulley 91, set on shaft 92. The latter shaft is mounted in bearings 98, secured to uprights 90 *A*, and is driven by rope 93, passing over pulley 94, set on this shaft, and pulley 95, set on the main driving-shaft *B*. Pulley 94 is integral with clutch-collar 135, set to loosely revolve on shaft 92. The other clutch-collar 95 136 is splined with shaft 92 and longitudinally movable thereon. Lever 131, operating also the clutch on the main driving-shaft *B*, and which is pivoted to the main frame at 134, embraces clutch-collar 136, and pins *Z*, 100 set in the lever, (see Fig. 1,) engage in a groove provided in the collar. The adjoining ends of collars 135 and 136 are serrated and fitted to clutch together. By shifting lever 131 collar 136 is moved on shaft 92 to 105 close or disengage the clutch. Two rolls 84 are set on shaft 87 to revolve in the paste-trough 83. Scrapers 96, mounted on rod 97, bear yieldingly against rolls 84 and regulate the supply of paste to be supplied to rolls 85, 110 transmitting the paste from rolls 84 to bars 86. Rolls 85 are mounted on the ends of rod 99, supported in clamp 100, which again is secured to push-bar 101 by set-screw 102. Push-bar 101 is hinged to rocking arm 21, secured to rocking shaft 32. By the rocking motions of the shaft 32 rolls 85 are thus reciprocated along the bars 86. 115

The motions of rolls 85 are guided by the segmental rail 104, which is embraced by prongs 103 of the clamp 100. The motions of rolls 85 are so timed that during part of the ascending motion of the movable frame they are brought forward and beyond the forward ends of bars 86, which are thus permitted to 120 pass above the rolls 85; but immediately after the bars 86 have reached the level of the upper surface of rolls 85 and come to a standstill rolls 85 are drawn rearwardly along the 125 bars and in contact therewith, thus depositing 130

the paste thereon. Rolls 85 then come to a standstill beyond the rear ends of bars 86, thus enabling the movable frame to descend again.

5 When the label to be affixed to the bottle is picked up by bars 86 and lifted from the pile and before it is brought in contact with the bottle, wipers 113, secured to levers 12 between plates 114 and 115, move from the position shown in Fig. 4 into the position shown in Fig. 5 and press the label upon the bottle, stretching it simultaneously from center toward the edge and affixing it thereto.

Levers 112 are fulcrumed to plate *h* by screw-bolts 111, and their rear arms are pivotally connected by rods 117 to levers 118 and 119, hinged to plate *i* of the movable frame by pins 128 and 129, respectively. Levers 118 and 119 are also fulcrumed to each other and to lug 126 by pin 125, whereby one lever (119) is actuated by the motions of the other (118) lever. Spring 123, adjustably secured in lug 126 by set-screw 127, acts with its ends on pivots 124, connecting rods 117 with levers 118 and 119, respectively. The function of this spring 123 is to produce a yielding tension upon wipers 113 through arms 112 during the period of affixing the label to the bottle. Rods 117 are adjustable lengthwise by swivel-joints 133, whereby the tension of wipers 113 upon the label during the affixing process is regulated.

In the lower edge of lever 118 recess 122 is provided to permit the lever to drop below the upper edge of slot *z* when roller 120 is at or near the left-hand end of this slot, then the recessed portion of lever 118 rests against roller 120, and as this roller moves in the slot *z* from left to right it comes in contact with straight portion of its lower edge, whereby lever 118 is forced upwardly and held in this position until roller 120 comes again at the end of the downward motion of the movable frame in contact with the recessed portion, whereupon lever 118 is brought again in its normal lowermost position by the action of spring 123. By this action of lever 118 and spring 123 arms 112 are moved together, and wipers 113 are brought nearer together underneath the bottle. 50 to hold and press the label against it. The upward motion of rods 117 is not restrained, except that spring 123 exerts a tension thereon, as above explained, and therefore wipers 113 are enabled to yield outwardly as they pass along the circumference of the bottle. Being, however, constantly pressed together and against the bottle, they stretch the label smoothly upon the bottle. When by the upward motion of the movable frame arms 112 and wipers 113 are brought to the level of rollers 85, they are drawn apart by the action of roller 120, passing to the straight part of the lower edge of lever 118 and lifting it to enable wipers 113 to pass clear of the ends of 55 rollers 85, as shown in Fig. 1. Arms 112 and

wipers 113 are then held in this position (apart from each other) during the operation of rollers 85 supplying bars 86 with paste during the entire downward motion of the movable frame and during the first part of its upward motion until after bars 86 have picked up and lifted the next label, as described above.

The machine is also provided with a device for stamping upon each label before the same is affixed to the bottle the date or some other mark or designation, as may be required. The stamping device (visible in Fig. 3) consists of rod 71, hinged to rocking arm 21, a printing-die 72, affixed on the end of this rod, bracket 74, secured to platform *b*, inking-pad 81, set thereon, connecting-rod 73, and the actuating mechanism mounted on the main shaft. Rod 71 is slid through a bore in the head of rod 73 and is longitudinally movable therein. It is reciprocated by the motions of rocking arm 21, so that the printing-die 72 is brought alternately in printing position (shown in Fig. 3) above the label and then again above the inking-pad 81, which is the inking position. The farther-on-described mechanism where- 90 with rod 71 is connected by the rod 73 effects the depressing and raising motions whereby the printing-die is brought in contact with the label to be printed on and again in contact with the inking-pad. Rod 73 is adjustable 95 lengthwise by means of swivel-joint *g*, connecting the two parts thereof.

All parts of the machine are driven and actuated from the main shaft B. The mechanism reciprocating the movable frame has been 100 already explained, and also the mechanism actuating pickers 86 and wipers 113. All these parts receive their motions from the crank-disk K by means of roller 120, slotted plate *i*, and levers 118 and 119, as hereinbefore explained.

Rocking arm 21, actuating the label-feeding mechanism by reciprocating rod 20, the printing mechanism by reciprocating rod 71, and the gumming or paste-supplying mechanism by reciprocating rod 101, is actuated by cam G, set on the driving-shaft B. Arm 21 is rigidly secured to rocking shaft 32 by set-screw 33. To the same rocking shaft is rigidly secured arm 34 by set-screw 35. On 110 the other end of arm 34 a roller 36 is set to loosely revolve on a pin set in the arm 34. This roller engages in groove F of cam G, shaped to produce a to-and-fro motion of the arm 34, whereby shaft 32 and arm 21, secured thereto, are rocked. Lever 60, operating pad 2 for holding the bottle firmly in position during the process of applying the label, is also actuated from the main driving-shaft B through rod 63 by the following mechanism. Rod 63 is 115 connected by forked plate 64 to spring 65, having the other end thereof attached by pin 66 to bar 67, set in the main frame. In this plate 64 is secured pin 68, and roller 69 is set to freely revolve thereon. Roller 69 is situated 120

in the path of the convex protuberance 70 of cam G, and when this protuberance comes in contact with roller 69 it pushes rod 63 up against the tension of spring 65, thus pressing pad 2 down upon the bottle and holding it firmly against the supports, and holds it there during the period of the operations of the other mechanisms applying the label to the bottle. Spring 65 draws rod 63 downwardly to raise pad 2 from the bottle. This latter position of the parts is shown in Fig. 3 of the drawings.

The mechanism actuating the printing device is constructed like the mechanism actuating the bottle-holding pad. Forked plate 75 connects rod 73 with spring 76, whose other end is fastened to pin 77, secured in the same rod 67. Roller 79, set on pin 78, secured in the plate 75, engages with cam I. This cam is a substantially circular cam provided with two concave recesses 80. (See Fig. 3 of the drawings.) The location of these recesses on the cam is such that one of them comes in contact with roller 79 right after rocking arm 21 moves the printing-die 72 in the position shown in Fig. 3 (Fig. 3 shows the position of the parts immediately after the concave depression passed out of contact with roller 79 and while the printing-die 72, though again lifted from the label whereon the imprint was made, is still in position above the label) and the other when the rocking arm 21 withdraws the printing-die 72 and brings it in position opposite the inking-pad 81. These recesses permit spring 76 to draw rod 73 downwardly, and thereby to press the printing-die 72 upon the label to print or upon the inking-pad to ink the die. In the arrangement shown in the drawings the printing or marking is produced on the reverse side of the labels. The same mechanism is, however, capable of printing the date or mark on the face of the label. This is accomplished by reversing the printing-die 72, placing the inking-pad on the bottom of flange 42, and by setting upon the main shaft B, actuating the rod 73, in place of cam I one provided with protuberances where recesses 80 of cam I are located.

When the machine is driven by power, a belt is drawn over pulley C, set to loosely revolve on shaft B, coupled with the shaft by means of a clutch, composed of toothed wheel E made integral with pulley C or rigidly connected therewith, collar v rigidly secured to the shaft adjoining the toothed wheel E, and lever e fulcrumed to it at m. In the end of the longer arm of lever e wedge u is secured, projecting therefrom toward the toothed wheel E. This wedge u is shaped to fit in the recesses between the teeth of the wheel E, and the end of lever e wherein this wedge u is secured is pressed against the wheel E by spring q, secured to the lever by screw 57 and set against a shoulder provided in collar v. The other arm s of lever e is bent toward the shaft. Its end is rounded

so that collar j, which is longitudinally movable on shaft B may be slid underneath, whereby arm s is moved farther away from shaft B and wedge u withdrawn from engagement with wheel E, thus disengaging the clutch. Collar j is operated by lever 131, fulcrumed on pivot t, (shown in Fig. 1,) set in socket 134, secured to the main frame. The lower arm of lever 131 is forked, and in the prongs thereof pins w are set, engaging in a groove of collar j. The upper arm of lever 131 is formed into a handle whereby this clutch is operated to start or stop the machine. This clutch when in engagement with the wheel E is automatically disengaged at every revolution of shaft B by hook 53, set on shaft 54 and pressed by spring 55 in such position that bevel edge n of lever e comes in contact with the correspondingly-beveled edge of the point 56 of this hook. In this position of hook 53 its point 56 is in the path of the beveled end of clutch-lever e. When this end reaches hook 53, it slides beyond its point, and thereby lever e is drawn away from wheel E and wedge u is withdrawn from its engagement with the teeth thereof. The clutch is then disengaged and the machine comes to a full stop, belt-pulley C and toothed wheel E then again rotating loosely on the driving-shaft. This stop occurs at the moment when the movable frame is in its lowermost position and the grippers are in contact with the pile of labels. The machine is then in position to receive a bottle to be labeled.

Hook 53 is connected by rod 51, hinged thereto, with lever 48, as hereinbefore explained. The length of rod 51 and the parts of the mechanism connecting lever 48 with plate 41 are so adjusted that when hook 53 is brought by the action of the spring 55 into horizontal position plate 41 is pushed a short distance outwardly toward bolster 23. When a bottle is set in its place in the machine, it is slightly pushed inwardly against plate 41. This plate yields, and thereby through the action of the bell-crank lever 48, hook 53 is drawn up and disengaged from clutch-lever e. When thus released, the clutch-lever is pressed by spring q against wheel E, wedge u slides in between the teeth of this wheel, thus again clutching shaft B to belt-pulley C, and the mechanisms of the machine are set in operation. When the bottle to which the label was applied is removed from the machine, (which is done when the movable frame is in its highest position and the labeling operation is completed,) spring 55 pushes hook 53 down again in the path of the clutch-lever e and withdraws wedge u from wheel E when brought in contact therewith by the revolution of shaft B. The clutch is then again disengaged and the machine stops.

The machine may also be operated by hand-power, for which the hand-wheel D is keyed to shaft B. In practical use, however, this

operating of the machine by hand will be limited to setting and adjusting the parts of the machine at the start or when changing the arrangements of the machine for differently-shaped bottles or for bottles of different sizes and the like.

This labeling-machine may be used for labeling of bottles of any kind or size, also for labeling of cans. The parts of the machine, 10 more particularly the grippers 86, with their levers 106, wipers 113, and levers 112, may be made adjustable or exchangeable to accommodate different shapes and sizes of bottles, cans, and the like.

15 I claim as my invention—

1. A labeling-machine comprising a stationary and a movable frame; a set of pickers and mechanism for holding them yieldingly in position; a set of wipers and mechanism for actuating the wipers, all mounted in the movable frame; an underneath support for the thing to be labeled, a receptacle for labels, a receptacle for paste, and mechanism for transmitting paste to the pickers; means for actuating the paste-transmitting mechanism; and mechanism for reciprocating the movable frame mounted in the stationary frame.

2. A labeling-machine comprising a stationary and a movable frame, a set of pickers and mechanism for holding them yieldingly in position; a set of wipers and mechanism for actuating the wipers, all mounted in the movable frame; a stationary support underneath the thing to be labeled and a clamp therefor and mechanism for actuating the clamp; a receptacle for labels, a receptacle for paste, mechanism for transmitting paste to the pickers, means for actuating the paste-transmitting mechanism; and mechanism for reciprocating the movable frame mounted in the stationary frame.

3. A labeling-machine comprising a stationary and a movable frame, a set of pickers and mechanism for holding them yieldingly in position; a set of wipers and mechanism for actuating the wipers, all mounted in the movable frame; an extensible support for the thing to be labeled, a receptacle for labels, a receptacle for paste and mechanism for transmitting the paste to the pickers; a shaft mounted in the stationary frame; mechanism for reciprocating the movable frame, mechanisms for actuating the paste-transmitting mechanism, a driving-gear and a clutch set on the shaft, and mechanism, connected with the extensible support, for operating the clutch.

4. A labeling-machine comprising a stationary and a movable frame; a set of pickers and mechanism for holding them yieldingly in position; a set of wipers and mechanism for actuating the wipers, all mounted in the movable frame; a support for the thing to be labeled, a receptacle for labels, a receptacle for paste, a die-holder, a printing-die secured to the die-holder, an ink-pad, mechanism for re-

ciprocating the die-holder, to and from the ink-pad and to and from the label; a receptacle for paste, means for transmitting the paste to the pickers, and mechanism for reciprocating the movable frame mounted in the stationary frame.

5. A labeling-machine, comprising a frame, a receptacle for labels, a set of pickers provided with means for applying paste to the labels, a receptacle for paste, means for conveying the paste from the receptacle to the pickers, mechanism for reciprocating the pickers between the paste-conveying means and the labels, a support for the thing to be labeled set between the receptacle for the labels and the paste-conveying means; a set of wipers, mechanism for reciprocating the wipers to and from the support for the thing to be labeled, and mechanism for yieldingly pressing the wipers against the thing to be labeled.

6. A labeling-machine, comprising a stationary frame, guideways set on the frame, a movable frame mounted on the guideways, a slotted plate on one end of the movable frame, a pair of levers pivoted to the plate above the slot and fulcrumed to each other; a spring connected to the fulcrum-pin and pressing the free ends of the levers over the slot; a pair of bell-crank levers pivoted to the other end of the movable frame, connecting-rods, each connecting one arm of the bell-crank levers with the free ends of the levers pivoted to the slotted plate; strips of yielding material affixed to the other arms of the bell-crank levers; a pair of double-armed levers, pivoted to the movable frame, picker-bars affixed one to each lever, a spring affixed to the movable frame and set against the double-armed levers; a support underneath the thing to be labeled, a receptacle for labels, a receptacle for paste, and mechanism for transmitting paste to the pickers; means for actuating the paste-transmitting mechanism; a driving-shaft, set in the stationary frame; a crank-disk secured to the driving-shaft, a pin set in the crank-disk, and a roller set on the pin and engaging with the slot of the movable frame.

7. Mechanism for feeding labels in an automatic labeling-machine comprising a stationary platform, a bracket secured to the platform, both provided with a bore; a feed-screw set in the bore, a receptacle for labels set on the feed-screw, a centrally screw-threaded ratchet-wheel set on the feed-screw between the platform and the bracket; a rock-shaft, an arm secured to the rock-shaft, a pawl attached to the arm and engaging with the ratchet-wheel, and mechanism for rocking the shaft.

8. Mechanism for applying paste to labels in a labeling-machine, comprising a receptacle for the labels; movable arms provided with picker-bars, and mechanism for reciprocating them to and away from the labels, a receptacle for paste, rollers revolving in the receptacle, a guide-rail set between the rollers

tating in the receptacle and the picker-bars; a saddle movably mounted on the rail, a shaft set in the saddle, rollers set on the shaft, and means for reciprocating the saddle along the 5 rail.

9. Mechanism for applying paste to labels in a labeling-machine, comprising a receptacle for the labels; movable arms provided with picker-bars, and mechanism for reciprocating them to and away from the labels, a receptacle for paste, rollers revolving in the receptacle, a guide-rail set between the rollers rotating in the receptacle and the picker-bars, a saddle movably mounted on the rail, a shaft set in 15 the saddle, rollers set on the shaft, a rocking shaft, an arm secured to the rocking shaft, a rod connecting the arm with the saddle and means for rocking the shaft.

10. Mechanism for printing or marking of labels in an automatic labeling-machine, comprising a platform for the labels, an ink-pad, a die-holder, a printing-die secured to the die-holder, a rocking shaft, an arm secured to the rocking shaft and to the die-holder, mechanism for rocking the arm, a shaft, a cam set on the shaft, a forked plate saddled on the shaft adjoining the cam, means for holding the plate yieldingly to the shaft, a pin set in the plate, a roller set on the pin and engaging with the 25 cam, and a connecting-rod connecting the plate with the die-holder.

11. Mechanism for automatically starting and stopping a bottle-labeling machine, comprising a driving-shaft, mechanism for actuating the movable parts of the machine set on 30

the shaft, a driving-pulley and a toothed wheel joined with the driving-pulley and both set to loosely revolve on the driving-shaft, a collar secured to the driving-shaft adjoining the toothed wheel, a clutch-lever in position 40 to engage with the toothed wheel and means for pressing the wedge in engagement with the wheel; a bevel-edged hook, pivotally connected with the frame of the machine, a spring acting on the hook to press it in the path of 45 the clutch-lever; a support for the thing to be labeled, a bell-crank lever mounted in the frame, and having one arm connected with the support, and a connecting-rod connecting the other arm of the bell-crank lever with the 50 hook engaging the clutch-lever.

12. Mechanism for holding the thing to be labeled in a labeling-machine, while the label is being applied thereto, the mechanism comprising a support for the thing to be labeled; 55 a double-armed lever fulcrumed in the frame of the machine above the support, a pad secured to one arm of the lever, a connecting-rod secured to the other arm of the lever, a shaft, a cam set on the shaft, a forked plate 60 affixed to the connecting-rod, and saddled on the shaft, means for yieldingly holding the plate to the shaft, a pin set in the plate, and a roller set loosely to revolve on the pin in position to engage with the cam.

JOHN FRED SCHNEIDER.
